TYPEWRITING MACHINE

George G. Going, Glenbrook, Conn., assignor to
Remington Rand Inc., New York, N. Y., a corporation of Delaware

Application February 24, 1933, Serial No. 658,397

9 Claims. (Cl. 197—147)

My invention relates to typewriting and like machines and more particularly to the platens thereof.

The main object of my invention, generally stated, is to provide an improved, substantially noiseless platen which is simple in construction, comparatively inexpensive to manufacture and highly effective in use. That is to say, a platen which is highly effective as such in use and yet 10 reduces the noise ordinarily produced from the impacts or hammer blows of the types thereon to the minimum and to such an extent as to be substantially noiseless.

To the above and other ends which will hereinafter appear my invention consists in the features of construction, arrangement of parts and combinations of devices set forth in the following description and particularly pointed out in the appended claims.

20 In the accompanying drawing wherein like reference characters indicate corresponding parts in the different views—

Fig. 1 is an enlarged, detail front view of one character of platen and some of the associated parts constructed in accordance with my invention, the platen being shown detached and with parts in section.

Fig. 2 is an enlarged, detail, transverse, sectional view of the same, the section being taken 30 on the line 2—2 of Fig. 1 and looking in the direction of the arrows at said line.

Fig. 3 is a fragmentary, detail, front view partly in section of a modified form of platen embodying my invention.

35 Heretofore many attempts have been made to produce a substantially noiseless platen, but for one reason or another they have all proved unsuccessful. Various materials, such for example as sponge rubber, have been used in the construction thereof, but none of them so far as I am aware has ever proved successful or has gone into use on the market. The employment of sponge rubber is of no practical use since the large number of air pockets in the rubber is apt to result in 40 the production of as much or more noise than the rubber sheathed platens ordinarily used. Moreover, the use of sponge rubber for a platen renders the platen ineffective as such aside from the noise which results from its use.

50 I have discovered that by making a solid homogeneous compact rubber platen or such a rubber platen or such a rubber platen with particles of cork embedded therein and the platen in each instance having a solid metal core, I am enabled to 55 produce a highly efficient platen which is sub-

stantially noiseless during the impacts of the types thereon, and such a platen has proved highly successful in use from every point of view.

When a compound of rubber and comminuted cork is used for the platen, as shown in Fig. 3, the cork is employed primarily to reduce the weight of the platen without destroying the qualities of the rubber or affecting the usefulness of the platen.

By the term "homogeneous" rubber, or rubber and cork, body portion of the platen, employed herein, I mean to distinguish from a platen body built up from laminations, layers or sheaths of rubber, or rubber and other materials such as cork. By the use of the term "compact" herein 10 in designating the character of the rubber, or rubber and cork, employed in making the body portion of the platen, I mean to distinguish from sponge rubber and the like which is not compact in its structure and could not be used effectively 15 for the purposes of the present invention. The quality and character of rubber that in practice I have found to be highly efficient corresponds substantially to that usually employed in making rubber feet for typewriting machines and for 20 making shoes for pneumatic tires.

25 By the use of the term "solid" platen, I mean to designate one which is not hollow, or is devoid of an open core extending therethrough.

I will now describe two specific embodiments of 30 my invention, as it is disclosed in the accompanying drawing.

Referring more specifically to Fig. 1 the cylindrical body portion 10 of the platen is made of a homogeneous mass of compact rubber that extends from the periphery of the platen substantially to the axis thereof, where it makes contact with an axially disposed solid metal rod or spindle 11. The "homogeneous", "compact" rubber is of 35 the character hereinbefore referred to. The solid spindle 11 is shown in the present instance to terminate at its ends before reaching the end plates 12 and 13 of the platen. The spindle therefore is free from contact with said platen 40 heads or with any metal part of the machine, being insulated therefrom by the rubber that constitutes the body of the platen, the spindle being carried and supported wholly by such rubber body. The spindle 11 in the construction 45 as thus far described constitutes a stiffening device at the core of the platen to maintain it sufficiently rigid to prevent a bending thereof out of its true cylindrical form. It will be seen that in this construction the rubber body 10 and 50 55

the spindle 11 constitute a platen devoid of an opening through the core thereof.

As shown in the present instance the end plates 12 and 13 are secured directly to the rubber body portion of the platen by screws 14 and 15 respectively and the end plates are in turn supported by the carriage, thus entirely insulating said body portion 10 from a metal-to-metal contact which if permitted might result in conveying vibrations from the body of the platen to the carriage and result in the production of some noise. However, it has been demonstrated in practice that the solid rubber platen of the character described with a supporting shaft or spindle on which the rubber body is molded and supported by said shaft in the carriage, is so highly effective as to reduce the noise that ordinarily results from hammer blows of the types against the platen to such an extent that it is negligible. Therefore, under the broader aspects of my invention the platen heads may be connected to the platen in any suitable manner.

The line spacing wheel 16 may be secured to the platen body by any suitable means. In the present instance I have disclosed the connection of the line spacing wheel to the platen through a platen clutch, which clutch may be of any suitable character but must be one that may be mounted outside of the body portion of the platen and does not require a hollow platen to receive it. The clutch shown in the present instance is similar to that employed in the No. 6 Remington Noiseless machine and is disclosed in the patent to Barney No. 1,579,749. Therefore, only a very general reference thereto will be made herein.

The line spacing wheel 16 is mounted to turn with and to permit an independent turning movement of the platen. As shown the ring-like line spacing wheel is adapted to turn freely on the platen head 12 and is provided with fine inwardly extending teeth 17 as well as outwardly extending teeth 18. A cover plate 19 is secured to the platen head 12 by machine screws 20, and holds the line spacing wheel against outward displacement from said platen head. The platen head 12 is channeled radially to receive and guide three pawls 21 which are stressed away from the teeth 17 by a circular contractile spring 22 which coacts with all of said pawls 21. Three plunger cams 23 coact with the inner ends of the pawls 21 and normally force the latter into engagement with the teeth 17 to connect the line spacing wheel to turn with the platen. This engagement is maintained by the excessive force of springs 24, each of which is stronger than and overcomes the force of the spring 22.

A release of the pawls 21 to enable the platen to be turned independently of the line spacing wheel is effected by a longitudinally movable spindle 25 that carries a ring 26 at the inner end thereof and is provided with a finger wheel 27 at the outer end thereof. The ring 26 is received in a cut-out 28 in each of the cams 23 and effects a withdrawal thereof when the finger wheel 27 is pulled out.

It will be understood that the line spacing wheel and clutch construction as a whole are detachably connected to the platen head 12 by screws 14 and are directly connected to the rubber platen body.

In the construction as shown the finger wheel 27 is detachably connected by the usual screws to a spindle 25 carried by the platen head 12.

In Fig. 3 I have shown a modified form of platen body 10^a made of rubber of the same general

character as that previously described with particles of comminuted cork embedded therein throughout the body as indicated at 10^b. This results in the provision of a materially lighter platen than is provided by the platen made wholly of rubber without destroying or affecting the qualities of the rubber to provide a substantially noiseless platen. The body 10^a is constructed, mounted and combined with the remaining parts of the platen as hereinbefore described and all of the characteristics of the previously described platen are inherent in combined rubber and cork body 10^a.

Various changes may be made in the construction, and certain features thereof may be employed without others, without departing from my invention as it is defined in the accompanying claims.

What I claim as new and desire to secure by Letters Patent is:

1. A substantially cylindrical noiseless platen for typewriting and like machines comprising a body portion of homogeneous compact rubber extending in a solid mass from the periphery of the platen substantially to the axis thereof and to and in contact with a single axially disposed solid metal spindle received therein, said rubber body portion and spindle constituting a solid platen devoid of an opening through the core thereof and the outer surface of said compact mass of rubber constituting the surface against which the types impact.

2. A cylindrical platen for typewriting and like machines comprising a body portion of homogeneous compact rubber extending in a solid mass from the periphery of the platen substantially to the axis thereof and to and in contact with an axially disposed metal spindle received therein, said spindle being supported wholly by the rubber body portion of the platen.

3. A substantially noiseless cylindrical platen for typewriting and like machines comprising a body portion of homogeneous compact rubber extending in a solid mass from the periphery of the platen substantially to the axis thereof and to and in contact with an axially disposed solid metal spindle received therein, said rubber body portion and spindle constituting a solid platen devoid of an opening through the core thereof, and end plates fixedly secured directly to the rubber body portion of the platen, thereby insulating said body portion of the platen from said end plate and preventing vibrations from being transmitted therethrough.

4. A cylindrical platen for typewriting and like machines comprising a body portion of homogeneous compact rubber extending in a solid mass from the periphery of the platen substantially to the axis thereof and to and in contact with an axially disposed metal spindle received therein, said spindle being supported wholly by the rubber body portion of the platen, and end plates secured directly to the rubber body portion of the platen.

5. A substantially noiseless solid cylindrical platen comprising a solid mass of homogeneous compact rubber with particles of cork imbedded therein throughout the mass, said mass extending from the periphery of the platen substantially to the axis thereof and reducing the noise ordinarily produced from the impact of the type bars on the platen to a minimum, the periphery of said mass constituting an even surface against which the types impact.

6. A substantially noiseless cylindrical platen

for typewriting and like machines comprising a body portion of homogeneous compact rubber with particles of comminuted cork imbedded therein, said body portion of the platen extending in a solid mass from the periphery of the platen substantially to the axis thereof and to and in contact with an axially disposed metal spindle received therein, said body portion and spindle constituting a solid platen devoid of an opening through the core thereof. 10

7. A cylindrical platen for typewriting and like machines comprising a body portion of homogeneous compact rubber with particles of comminuted cork imbedded therein, said body portion extending in a solid mass from the periphery of the platen substantially to the axis thereof and to and in contact with an axially disposed metal spindle received therein said spindle being supported wholly by the body portion of the platen. 15

8. A substantially noiseless cylindrical platen for typewriting and like machines comprising a

body portion of homogeneous compact rubber with particles of comminuted cork imbedded therein, said body portion extending in a solid mass from the periphery of the platen substantially to the axis thereof and to and in contact with an axially disposed metal spindle received therein, said body portion and spindle constituting a solid platen devoid of an opening through the core thereof, and end plates secured directly to the body portion of the platen. 5

9. A cylindrical platen for typewriting and like machines comprising a body portion of homogeneous compact rubber with particles of cork imbedded therein, said body portion extending in a solid mass from the periphery of the platen substantially to the axis thereof and to and in contact with an axially disposed metal spindle received therein, said spindle being supported wholly by the body portion of the platen, and end plates secured directly to the body portion 15 20 of the platen.

GEORGE G. GOING.
